CLAIM

(21) Appl. No.: **29/120,540**

I claim the ornamental design for a grip for headshell of electric connector, as shown and described.

(22) Filed: **Mar. 21, 2000**

DESCRIPTION

(51) LOC (7) Cl. **13-03**

FIG. 1 is a perspective view of the design of a grip for headshell of electric connector, the dotted lines do not form part of the design of the present invention;

(52) U.S. Cl. **D13/154; D8/303**

FIG. 2 is a left hand view of the design of the present invention;

(58) Field of Search D13/144, 154,

FIG. 3 is an elevated front view, which is the same as a back, bottom, and top view;

D13/156; D8/300, 303, 312; 74/551.9;
174/46; 439/625, 668, 901; 16/421, 430,
DIG. 12

FIG. 4 is a right hand view of the present invention; and,

D. 31,257 * 7/1899 Mather D8/303

FIG. 5 is an elevated front view of the second embodiment of the invention in a smaller configuration, the back, bottom, and top views being identical to the front view.
